LEWIS WAKEFIELD, OF MINNEAPOLIS, MINNESOTA.

Letters Patent No. 88,242, dated March 23, 1869.

IMPROVEMENT IN AXLE-BOX

The Schedule referred to in these Letters Patent and making part of the same.

To all whom it may concern:

Be it known that I, LEWIS WAKEFIELD, of Minneapolis, in the county of Hennepin, and in the State of Minnesota, have invented certain new and useful Improvements in Axle-Boxes; and do hereby declare that the following is a full, clear, and exact description thereof, reference being had to the accompanying drawings, and to the letters of reference marked thereon.

The nature of my invention consists in the construction of an axle-box, or journal-box for carriages.

In order to enable others skilled in the art to which my invention appertains, to make and use the same, I will now proceed to describe its construction and operation, referring to the annexed drawings, which form a part of this specification, and which represent a longitudinal section of my invention.

A represents the axle-box, upon one end of which is cast a solid bevelled flange, B, and the opposite end is cut with a screw-thread, which receives the bevelled nut-flange D.

As the wood will not shrink endwise, the nut D will secure the box in the hub with perfect tightness, without any wedging or other appliances which cause deviations from the exact centre. And should, by any means, the box become loose, it will only be necessary to tighten the nut D by screwing it further in.

Having thus fully described my invention,

What I claim as new, and desire to secure by Letters Patent, is—

The axle-box A, provided at one end with a solid bevelled flange B, and at the other with screw-threads, which receive the bevelled nut-flange D, substantially as and for the purposes herein set forth.

In testimony that I claim the foregoing, I have hereunto set my hand, this 4th day of September, 1868.

LEWIS WAKEFIELD.
